UNITED STATES PATENT OFFICE.

JOHN A. FREY, OF SILVER SPRING, MARYLAND.

BOILER AND SUPERHEATER.

1,097,542.

Specification of Letters Patent. Patented May 19, 1914.

Application filed February 18, 1914. Serial No. 319,517.

To all whom it may concern:

Be it known that I, JOHN A. FREY, a citizen of the United States, and a resident of Silver Spring, in the county of Montgomery and State of Maryland, have made certain new and useful Improvements in Boilers and Superheaters, of which the following is a specification.

My invention relates to improvements in a combined boiler and superheater, and it consists in the combinations, constructions, and arrangements herein described and claimed.

An object of my invention is to provide a device by means of which steam which is generated in a boiler may be returned to a superheater disposed within the combustion chamber of the boiler whereby the steam is superheated for use in metallurgical operations, and in which steam at a lower pressure may be taken from the same boiler to run an engine or for any other suitable purpose.

A further object of my invention is to provide a boiler and superheater of the type described in which the superheater comprises a coil which may be easily removed from the boiler structure or may be replaced therein without the necessity of tearing down or dismantling the boiler.

A further object of my invention is to provide means for suspending the coil within the combustion chamber and for centering it therein.

A further object of my invention is to provide means for introducing fuel either below or above the coil.

Other objects and advantages will appear in the following specification and the novel features of the device will be particularly pointed out in the appended claims.

My invention is illustrated in the accompanying drawings forming part of this application in which—

Figure 1 is a plan view of the device, Fig. 2 is a perspective view of the device, Fig. 3 is a sectional view through the device on the line 3—3 of Fig. 1, Fig. 4 is a section along the line 4—4 of Fig. 3, Fig. 5 is a section along the line 5—5 of Fig. 4, Fig. 6 is a section along the line 6—6 of Fig. 4, Fig. 7 is a perspective view of the means for supporting the coil, Fig. 8 is a perspective view of a portion of the removable door plate, and Fig. 9 is a side view of the coil.

Referring now to the drawings I have

shown therein an outer cylindrical casing 1 and an inner cylindrical casing 2, the space 3 between these inner and outer casings serving as a part of the boiler proper. Extending at right angles to the casings 1 and 2 is a cylindrical casing 4, which is supported by standards 4^a, and which is provided with tubes 5 leading to a stack 6. A clean out door 4^b is provided as shown in Fig. 2. The interior of the cylinder 4 is in communication with the space 3 between the inner and outer casings 1 and 2. Surmounting the device is a steam dome 7 from which a pipe 8 leads to the engine (not shown).

As will be seen from Figs. 3 and 4 the grate 9 is disposed at a suitable height to leave an ash pit 10 underneath it. The space 11 inside the inner casing 2 constitutes the combustion chamber, and it does not have to be lined with refractory material, because of the presence of the water in the space 3 between the inner and the outer casing. As will be readily seen from Figs. 3, 4 and 7, the inner casing 2 is provided with wedge-shaped lugs 12 which are secured to the inner face of the casing, and which are arranged to receive brackets 13 which are provided with channels 13^a to permit the bracket to be slipped over the lugs 12. These brackets have inwardly extending portions 13^b whose purpose will be explained later.

The outer casing 1 of the boiler is provided with a removable door plate 14 which bears upper and lower hinged doors 15 and 16 respectively. The inner side of the door plate 14 has secured to it a chute 17. Openings such as that shown at 18 in Fig. 8 are provided between the upper and lower doors into which tubes 19 of the shape shown in Fig. 3 may be inserted, these tubes being provided with transparent refractory material, such as mica 20, through which the condition of the combustion chamber or the coil therein may be determined. In some instances it may be advisable to omit the tubes and make use of the openings 18.

The coil 21 which forms the major portion of the superheater is best shown in Fig. 9. As will be observed it is provided with upper and lower threaded ends 21^a and 21^b respectively. These ends are arranged to project through openings such as that shown at 22 in Fig. 8. The upper end of the coil is connected with a reducing elbow 23, the latter being in turn connected with a pipe 10.

24 by means of a union 25. The pipe 24 is provided with a valve 26 and communicates with the top of the steam dome 7. A branch pipe 28 is provided at its end with a removable plug 29. A gage 30 is preferably located on this branch pipe. The lower end 21^b of the coil is connected by means of the pipe 31 with pipes 32 and 33 leading to roasters 34 and 35 respectively, these roasters being preferably of the type set forth in my prior Patent No. 1,081,732.

As will be seen from the drawings the coil is supported by the laterally extending portions 13^c of the brackets 13, these portions entering between the convolutions in the manner clearly shown in Fig. 3.

From the foregoing description of the various parts of the device the operation thereof may be readily understood.

20 Fuel may be introduced into the combustion chamber either through the upper door 15 or the lower door 16 and the products of combustion pass upwardly, heating the walls 2 and also the coil 21, thence through 25 the tubes 5 and out of the stack. The steam which is generated in the boiler proper passes to the steam dome 7 and may be used for running an engine or for any other suitable purpose. When the valve 26 is open 30 the steam passes down through the pipe 28, through the elbow 24, and into the coil 21. Here it is superheated by the same fuel which heats the water. Owing to the fact 35 that the coil 21 is spaced from the inner wall the steam in the coil is superheated to a maximum degree and may then be admitted into the roasters through the pipes 32 or 33, valves being provided in these pipes for directing the flow in accordance with 40 the conditions. The condition of the interior of the device may be observed at any time through the tubes 19, while the pressure of the superheated steam may be observed 45 through the gage 30. If it should be desirable at any time to pass in fuel such as hydrocarbon in liquid or gaseous form with the superheated steam this may be done by removing the plug 29 and making connection at this point with the source of supply of said auxiliary fuel.

Owing to the fact that the coil 21 is not in contact with a cooling medium the temperature of the coil will, of course, be very high. If the coil should burn out it may 55 be very easily replaced by proceeding in the following manner. The pipes 31 and 23 are disconnected from the ends of the coil 21, the door plate 14, which, it will be observed from Fig. 2, is held in place by means of pivot clasps 36, is now removed and the coil 60 may be lifted from the brackets 13 and passed through the opening left when the door plate is removed. A new coil may be readily inserted by reversing these operations.

There are several advantages from a combined boiler and superheater of this type. In the first place fuel is economized since the same fuel which is used to heat the water to produce steam at low pressure for driving the engine is used to heat the coil. The superheater has no refractory wall, because the water jacket 3 serves to prevent the burning out of the inner casing 2. The ready removal of the coil prevents any prolonged delays due to the burning out of the coil. The high heat to which the coil is subjected renders it liable to burn out, but it also gives the advantage of obtaining superheated steam at a high temperature, which is essential for the proper working of the roasters.

In case the brackets 13 should burn out they may be removed, and others provided, and this again takes but a very short time. It will be observed that by attaching the chute 17 to the door plate 14 the chute is removed with the door plate so as to permit the coil to easily pass through the side of the device. Furthermore the chute 17 prevents the accumulation of fuel between the coil and the tubes 19. Thus the condition of the coil may be at all times observed. The fuel which is delivered in the upper door is deposited in the center of the coil, and hence the latter may come into intimate contact with the fuel itself.

I claim:

1. In a combined boiler and superheater, an outer casing, an inner casing, the space within the inner casing constituting a combustion chamber, and the space between the inner and outer casings constituting a water chamber, a removable door plate carried by said outer casing, a superheater coil normally disposed within said combustion chamber, and means for removably supporting said superheater coil, said coil being of such a size as to pass readily through the opening left when the door plate is removed from the outer casing.

2. In a combined boiler and superheater, a water chamber of annular cross section, the space within the water chamber constituting a combustion chamber, a superheater coil disposed within said combustion chamber, and brackets for suspending said superheater coil and for spacing said superheater coil from the walls of the annular boiler.

3. In a combined boiler and superheater, a water chamber of annular cross section, the space within the water chamber constituting a combustion chamber, a superheater coil disposed within said combustion chamber, removable brackets secured to the inner walls of said annular water chamber, a superheater coil suspended from said brackets, said coil being spaced from the walls of said annular boiler, said boiler being provided with an opening for permitting the

passage of the superheater coil into the interior of the boiler, and a removable plate for covering said opening.

4. In a combined boiler and superheater, 5 a water chamber of annular cross section, the space within the water chamber constituting a combustion chamber, a superheater coil disposed within said combustion chamber, removable brackets secured to the inner 10 walls of said annular water chamber, a superheater coil suspended from said brackets, said coil being spaced from the walls of

said annular boiler, said boiler being provided with an opening for permitting the passage of the superheater coil into the interior of the boiler, a removable door plate having upper and lower doors, said plate having a chute for delivering fuel from the upper door into the interior of the coil. 15
